UNITED STATES PATENT OFFICE.

ORVILLE E. ALLEN, OF HORNELL, NEW YORK.

AXLE SUSPENSION.

1,008,102.

Specification of Letters Patent.

Patented Nov. 7, 1911.

Application filed May 4, 1910. Serial No. 559,331.

To all whom it may concern:

Be it known that I, ORVILLE E. ALLEN, a citizen of the United States, residing at Hornell, in the county of Steuben and State of New York, have invented new and useful 5 Improvements in Axle Suspensions, of which the following is a specification.

This invention relates to an improvement in the axle suspension of motor vehicles and 10 its principal objects are to provide an organization wherein the bearing parts and their cushioning adjuncts may be assembled in a unitary and self-contained manner with respect to an element hereafter termed a 15 "driving lug" and wherein the parts of the axle bearing and other associated parts have a novel and advantageous relation to one another and to the driving lug.

An embodiment of the invention is illustrated by way of example in the accompanying 20 drawings, which contain Figure 1, a view in central vertical section, of the improved axle suspension; Fig. 2, a horizontal section on the line 2—2 of Fig. 1; Fig. 3, a 25 detail plan view of a seat block to be hereinafter specifically referred to; Fig. 4, a detail plan view of the sections of a socket member or plate which is associated with the seat block shown in Fig. 3; Fig. 5, a dia- 30 grammatic plan showing a practical application of the axle suspension; Fig. 6, a view in central vertical section of an alternative construction of air pumping adjunct; Fig. 7, a detail elevation in part section of the 35 compressed air operated braking device; and Fig. 8, a detail elevation in part section of the same device and in a plane at right angles to the plane of Fig. 7.

Similar characters of reference designate 40 corresponding parts throughout the several views.

The means for transmitting power in a positive manner from the driving axle 1 to the vehicle frame 2, consists preferably of 45 a plate, shaped and proportioned with regard to requisite strength and having a central vertical slot 3 terminating short of the upper end of the plate and opening at the lower end thereof. The portions of the 50 plate on each side of the slot may be aptly called "driving lugs" and are designated by the numeral 4. The driving lugs are each constructed with portions of a laterally and inwardly projecting flange, as 5, which 55 circumscribes the slot, and has at its lower end out-turned portions, as 6.

The end portions of the axle 1 project through the adjacent slots 3 and are journaled in bearings, each comprising an upper section, as 7, a lower section, as 8, and an intervening bushing, as 9, which directly surrounds the axle and is provided at its sides with flanges, as 10, against which the sections 7 and 8 are held. 60

The axle is vertically movable with relation to the frame and the slots 3 constitute guides for the axle in its vertical movements. To cushion such movements, the usual elliptic springs (not shown) are employed, and in addition to these elliptic springs helical 65 springs may be and preferably are provided to serve as auxiliaries to the elliptic springs, both as to normally assisting in cushioning direct and reactionary shocks and as to wholly replacing the elliptic springs (in 70 case of their breakage), for a limited period. The helical springs are arranged in the slots 3, the one, 11, being positioned above the axle and the other, 12, being positioned below the axle. 75

To maintain the assemblage of the springs, seat blocks of suitable construction are provided, the blocks for the spring 11 being designated by the numerals 13 and 14, and the blocks for the spring 12 being designated 80 by the numerals 15 and 16. The several seat blocks are of H-shaped outline, being thus provided with lugs, as 17, which project in pairs from the ends of the blocks and straddle the flanges 5. The blocks 14 and 15 85 which are juxtaposed, maintain the assemblage of the bearing sections 7 and 8 (which are also of H-shaped outline) and are connected by bolts, as 18, which extend through the lugs 17 aforesaid. The blocks 14 and 15 90 which are juxtaposed, maintain the assemblage of anti-friction bearing pieces, as 19, which are interposed between the same and the flanges 10, and bear against the flanges 5. In order that the axle bearings and their adjuncts may be 100 assembled and disassembled as a self-contained structure, the end convolutions of the springs 11 and 12 are permanently secured to the several seat blocks aforesaid and are seated in dished faces 20 of said blocks. To 105 maintain the assemblage of the self-contained structure in the slot 3, the upper block 13 is fixedly held at the upper end of said slot as by screw fastenings 21 which extend through the flanges 5 and the lower 110 block 16 is similarly held as by screw fastenings 22. The lower block also rests upon a

plate, as 23, which is secured to the outer turned flange portions 6, as by fastenings 24 and which relieves the fastenings 22 of stresses, the flanged upper central portion 25 of each driving lug plate performing a similar function with relation to the fastenings 21.

The adjunctive mechanism for developing compressed air is associated with the axle suspension above described and as a part of the self-contained structure of said axle suspension. Said compressed air developing mechanism comprises essentially, a pump, the operation of which is incident to the vibratory action of the frame, a storage tank or reservoir, and a connection between said pump and said storage tank or reservoir.

The pump comprises, preferably, two telescopically related cup-shaped members, the one, 26, being associated with the block 13 and the other, 27, being associated with the block 14, and telescoping into the member 26. In the construction shown in Fig. 1, the member 26 is threaded into the seat block 13, and the member 27 terminates in a spherical head, as 28, which is held, universal joint fashion, in a similarly shaped recess provided for by the assemblage of a pair of members 29, each of semi-disk shape, in a threaded recess 30, formed concentrically in the upper face of the block 14. The members 29 thus constitute, in effect, a split socket for the reception of the spherical head 28. The member 27 is provided in its lower portion with apertures, as 31, which open to a valve seat and which are controlled by a floating valve, as 32, held in proper relation by a spider or web, as 33.

Fig. 6 shows an alternative pump construction, in which the members 26 and 27 are associated with their seat blocks by ball and socket fastening devices, generally similar in construction to the fastening of the member 27 shown in Fig. 1 and above described, but differing therefrom in that the socket parts 29 are not threaded and are simply set into the recesses provided therefor, being held therein by threaded rings, as 34.

In Fig. 5, an axle suspension, as A, is shown at each side of the vehicle and it follows that the compressed air developing adjuncts may be, and preferably are, employed in duplicate. The storage tanks or reservoirs are designated by the numeral 35 and are connected to the respective pumps, by which they are supplied, by pipe or hose sections 36, each provided with one or more check valves, as 37, and opening into the upper end of the members 26, as shown in Figs. 1 to 6. The air stored in the tanks 35 may be advantageously utilized as a medium to set the brakes and for this purpose the pressure operated parts of the braking devices are connected, pneumatically, with a pipe, as 38, which leads from the tanks or

reservoirs 35 and which is provided with a valve, as 39, opened or closed in any suitable manner, *e. g.* by a lever (not shown) connected to a link, as 40, which is in turn connected to a crank arm at the end of the stem 70 of said valve.

The construction of the braking devices is shown in detail in Figs. 7 and 8. Each braking device consists essentially of a rim, as 41, which is fixedly mounted on the inner 75 side of the wheel, concentric with the hub, and an expansible band, as 42, which is arranged concentrically within the rim and which, when expanded, engages frictionally with the inner surface thereof. It is proposed to provide a braking device adjacent each wheel, in order that a more efficient braking action may be had. In Figs. 7 and 8, the braking devices are shown in their application to one of the front wheels, and 85 the means for expanding and contracting the band 42 comprises elements which are carried by the knuckle post 43. For this purpose said knuckle post has at its under side a laterally projecting web, as 44, and 90 at its upper side a laterally projecting stud, as 45. The web 44 carries a stationary cylinder, as 46, within which a cup-shaped piston, as 47, is axially slidable. Upon the stud 45 a lever, as 48, is pivoted. One end 95 of the band 42 is connected to the outer end of the lever 48 and the other end of said band is connected to said lever at a point inwardly of the pivot 45. The inner end of the lever 48 is connected by a sliding 100 pivot device with an extension of the piston 47. The pipe 38 is provided with lateral branches 49 and these are in turn connected to the several cylinders 46 by flexible hose sections, as 50, which allow of the necessary 105 turning movement of the knuckle posts and wheel studs. The tendency of the band 42 is to contract. In setting the brakes the valve 39 is opened and compressed air is admitted to the cylinders 46. The pistons 47 110 are thus forced outwardly and, through the agency of the levers 48, cause the bands 42 to expand into frictional braking engagement with the rims 41. The braking devices which are applied to the rear wheels 115 are similarly constructed. In this instance, the web 44 and stud 45 are provided on the axle bearing, as will be obvious. The valve 39 may be of any well known construction which, in one position, will admit air to the 120 braking devices and, in another position, as when the brakes are to be released, will vent the air therefrom.

From the foregoing description, it will be readily apparent that the driving lugs 4 125 transmit power from the axle to the frame in a certain and positive manner and thus relieve the springs of all stresses from this source. The efficient life of the springs is thus prolonged and their cushioning action 130

is rendered more efficient, not only because it is permitted in an uninterrupted manner but also because it is assisted, as well by the auxiliary springs 11 and 12 as by the pumping mechanism. The operation of the latter is incidental to the natural vibration of the frame and requires no power to be taken from the engine, and the assemblage of the pumps in association with the suspensions 5 has the advantages of compendiousness, inexpensiveness, and coöperation with the suspensions. The construction provides for a permanent charge of compressed air and the utilization of this compressed air for setting 10 brakes dispenses with taking power from the engine and provides for a quicker, easier, and more certain brake setting operation. The arrangement is of advantage in that it provides for the application of a braking 15 device to each wheel and the braking devices are of such construction that no special design of brake cluster or of knuckle post is necessitated.

Having fully described my invention, I 25 claim:

1. The combination with a vehicle frame and its axle of a member secured at each side of the frame and consisting of a plate having a vertical slot which extends to its lower 30 edge and terminates short of its upper edge, an axle bearing slidably lengthwise of the slot and including separably related parts arranged at opposite sides of the axle and connected by bolts, cushioning springs fitted 35 against the axle bearing at opposite sides

thereof, blocks arranged at the upper and lower ends of the slots, the springs seating against said blocks and against said separably related parts and a plate removably attached to the member and closing the lower 40 end of the slot.

2. The combination with a vehicle frame and its axle of a member secured at each side of the frame and consisting of a plate having a vertical slot, springs for cushioning the movements of the axle and an axle bearing associated with each plate and comprising bearing sections having lugs projecting in pairs from each end thereof and overlying the opposite sides of the plate, a bushing 45 50 immediately surrounding the axle, the bushing having longitudinal flanges at the sides thereof, members fitted against the bearing sections and having lugs projecting in pairs from each end thereof and overlying the opposite sides of the plate, bolts passing through the several named lugs and binding together the parts of each axle bearing, and bearing pieces arranged between the edges of the 55 60 slots and the bearing sections and also between the flanges of the bushing and the members.

In testimony whereof I have hereunto set my hand in presence of two subscribing 65 witnesses.

ORVILLE E. ALLEN.
